GLASS GRINDING AND POLISHING
MACHINE

Hubert J. Capellman, Sr., South Chicago, Ill.

Application May 23, 1930. Serial No. 455,117

7 Claims. (Cl. 51—59)

This invention relates to certain novel improvements in glass grinding and polishing machines and has for its principal object the provision of an improved construction of this character which will be highly efficient in use and economical in manufacture.

Another object of the invention is the provision of a construction of the character described herein by means of which the edges of glass plates or like articles may be rapidly finished with a minimum expenditure of labor.

The new finishing machine includes a movable abrasive, a trackway, a carriage movable along the trackway to and from the abrasive, and article holding means on the carriage movable, relative to the carriage, to and from the abrasive; and other objects of the invention are: to provide a novel article-holding means; to provide a novel arrangement of the article holding means on the carriage; and to provide a novel arrangement for moving the article-holding means, relative to the carriage, to and from the abrasive.

Other objects will appear hereinafter.

The invention consists in the novel combination and arrangement of parts to be herein-after described and claimed.

The invention will be best understood by reference to the accompanying drawings, showing the preferred form of construction and in which:

Fig. 1 is a sectional view taken substantially on the line 1—1 in Fig. 2, showing a preferred construction of the machine;

Fig. 2 is a sectional view substantially on the line 2—2 in Fig. 1;

Fig. 3 is a detailed sectional view taken substantially on the line 3—3 in Fig. 1;

Fig. 4 is a fragmentary perspective view showing certain features of the invention;

Fig. 5 is a perspective view of a unit embodied in the invention;

Fig. 6 is a modified form of construction of a block of abrasive material embodied in the invention; and

Fig. 7 is a perspective view of the invention assembled for use.

Among the objects of this invention is the provision of a machine which will expeditiously grind and polish the edges of glass plates which are adapted to be mounted and used in various ways in which such plates are used in the arts, such as in automotive vehicles windshields, doors, or the like. Referring to the drawings wherein a preferred construction of the invention is shown, and referring more particularly to Fig.

7, the invention includes a carriage 10 which is adapted to support a plurality of glass plates 11 and this carriage is adapted to be fixed in position on a housing 12 in which are disposed mechanisms actuated by a motor 13 which reciprocally moves a slab 14 of suitable abrasive material against the edges of the glass plates. In arranging the invention for use, carriage 10 is slidably mounted on a platform 15 which includes the braces 16 and 17 which are secured to leg portions 18 by suitable connecting elements such as nails 19 or the like. Provided on the platform 15 are guiding troughs 20 which are adapted to communicate with and to be disposed in alignment with guiding troughs 21 provided in the housing 12. The carriage 10 includes legs 22 which are slidable in the troughs 20 and 21 so that when the glass plates 11 are inserted into position, in a manner to be described presently, the carriage 10 may be moved slidably from the platform 15 onto the housing 12.

The carriage 10 includes a movable table 23 in which the plates 11 are secured in a manner to be described presently and this table is movable vertically through the medium of a bar 24 and counterbalance weights 25 which are supported by cables 26 suspended on pulleys 27, which are attached to the table 23. Included in the carriage 10 are side portions 28 which provide supporting legs 29 and foot portions 30. Disposed between the legs 29 and attached thereto by means of suitable connecting elements such as screws 31 are end portions 32.

Referring now particularly to Figs. 1 and 2, it will be seen that there are provided on one side of the carriage 10 two similar brackets 33 which provide right angularly extending flanges 34 and these brackets are secured to the legs 29 by means of suitable connecting elements such as screws 35. Projecting outwardly from the brackets 33 and secured thereto in any approved manner are studs 36 and pivotally mounted on these studs are arms 37, in the opposite end portions of which bar 24 is mounted in any approved manner such as by riveting. Pivotally mounted on the arms 37 by means of suitable connecting elements such as studs 38 are the end portions 39 of the table 23. Secured in any approved manner to these end portions 39 of the table 23 are the cables 26 which, at their opposite ends, are secured in any approved manner to the counterbalance weights 25. These cables are guided in the pulleys 27 which are rotatably supported on stub shafts 40, and these

- shafts 40 are supported by brackets 41 which include foot portions 42. The foot portions 42 are secured to the end portions 32 by means of suitable connecting elements such as screws 43.
- 5 It will be manifest, therefore, that when the bar 24 is raised and lowered on the supporting studs 36 the table 23 will likewise be raised and lowered since the bar 24 is attached to the end portions 39 of the table and it will be seen that as 10 the table 23 is raised the counterbalance weights 25 will be lowered on cables 26.
- Included in the table 23 and extending between the end portions 39 are side portions 44 and 44' which are secured to the end portions 39 in any approved manner such as by welding and supported by these side portions 39 are the mechanisms now to be described for clamping the glass plates 11 in position and for turning these plates to expose the different edges of the 20 plates to the action of the abrasive slab 14. In this connection there is provided a cylindrical opening 45 in the side portion 44' and projecting through this opening is a hub 46, at the inner end of which is a disc 47 carrying a ball race 25 48. A centrally disposed cylindrical opening is formed in the hub 46 and projecting through this opening is a shaft 49 which carries a disc 50 at its inner end. Diametrically opposed aligned openings are provided in the discs 47 and 50 and 30 adapted to be projected through these openings are floating pins 51 whereby to lock discs 47 and 50 together for mutual rotatory motion. Carried by the hub 46 exteriorly of the side portion 44' of the table is a collar 52 which includes a flanged portion 56 and this collar is secured to the hub 46 by means of a stud 53. Referring particularly to Fig. 5 it will be seen that a notch 57 is provided in the flanged portion 56 of collar 52. To effectuate locking the hub 46 and 40 attached disc 47, and shaft 49 and attached disc 50 against rotatory movement when the glass plates 11 and resilient plates 55 are in working position, I provide an arm 58 which is secured to the side portion 44 of the table 23 by means 45 of a suitable riveted stud 59. A tongue 60 is formed in the arm 58 and when this tongue is engaged in the notch 56 it will be seen that the collar 52 and discs 47 and 50 are locked against rotatory movement.
- 50 The outer end portion of the hub 46 is threaded interiorly as indicated at 53 and a threaded thumb screw 54 is threaded therein. It will be manifest, therefore, that when the thumb screw 54 is threaded into the hub 46 the 55 inner end of this screw will abut the outer end of shaft 49 and as the thumb screw 54 is tightened the shaft 49 and attached disc 50 will be moved inwardly and disc 50 will abut one of the plates 55 of resilient material such as rubber or the like which are provided for securing a gripping action between and against the glass plates.
- A cylindrical opening is provided in the side portion 44 of table 23 and projecting through this opening is a hub 61 which carries a disc 62 at its inner end and provided between the outer side of the disc 52 and the inner side of the side portion 44 is ball race 63. Projecting 65 outwardly from the periphery of the hub 61 adjacent the outer end portion thereof is a key 64. A sliding collar 65 is provided on the hub 61 outwardly of the side portion 44 of table 23 and this collar is mounted for sliding engagement on hub 61 by means of a spring 66, 70 one end of which is secured to the hub 61 and the opposite end of which is attached to the collar 65 in any approved manner such as by screw 67. A slot 68 is provided in the collar 65 and projecting upwardly in this slot is the key 64. It will be apparent, therefore, that when collar 65 is retracted against the force of spring 66 the collar will be guided on the hub 61 by means of the key 64 and when collar 65 is in retracted position the hub 61 and attached disc 62 are rotatable therewith since the key 64 on hub 61 engages the collar 65 in the slot 68. Suitable radial arms 69 are provided in the collar 65 to facilitate reTRACTING the collar 65 and likewise to facilitate 80 rotating the collar 65, hub 61 and disc 63.
- 85 Assuming that the glass plates 11 and adjacent resilient plates 55 have been disposed in position, as best shown in Figs. 2 and 7, it will be manifest that when the thumb screw 54 is screwed inwardly the inner end thereof will abut the outer end of hub 49 and disc 50 attached to hub 49 will be forced into gripping engagement against the resilient plates 55 and the glass plates 11 and these plates in turn 90 will be forced against the disc 62. In this manner the glass plates 11 are retained in position during the grinding and polishing of the edge portions of the glass plates which action will be described hereinafter. To facilitate turning 95 the different edges of the plates into polishing position I provide a flanged portion 70 on the collar 65 and formed at 90° intervals in this flanged portion are suitable notches 71 which are adapted to engage a tongue 72 which projects from the side portion 44. It will be manifest, therefore, that when the collar 65 is reTRACTED on hub 61, hub 61 and attached disc 62 may be rotated so that each of the edges of the glass plates 11 may be brought into contact 100 with the abrasive slab 14, and when the desired edges of the glass plates are disposed parallel to the slab 14 and collar 65 released, the tongue 72 will engage in the desired one of the notches 71, preventing rotation of disc 62, and 105 in this manner the glass plates are secured in polishing position and prevented against rotatory movement during the grinding and polishing operation to be described presently.
- 110 The housing 12 is preferably mounted on any flat surface providing a suitable base 76 to which the housing may be secured by means of suitable connecting elements such as screws 77 or the like. In this connection I make the platform 15 of a suitable design and height so that the 115 guiding troughs 20 in the platform are in parallel vertical and horizontal alignment with the guiding troughs 21 provided in the housing 12. The housing 12 may be formed of any suitable 120 material as will best serve the purpose and included in the housing are side portions 73 and end portions 74 which are secured together by means of suitable connecting elements such as screws 75. Formed in the end portions 74 on 125 the inner sides thereof are offset portions 78 which provide shoulders 79 and mounted on these shoulders are rails 80 which have longitudinally extending slots 84 formed therein 130 providing flanges 81 and 82. These rails 82 are secured to the sides 73 of the housing by means of suitable connecting elements such as screws 83.
- 135 There are provided on the rails 82 longitudinally extending flanges 85 interiorly of which 140
- 140
- 145
- 150

are grooves 86, and shelves 87 are provided inwardly of the grooves 86. In this connection wheels 88 are mounted on the carriage 10 in any approved manner such as by means of suitable pins 89 and these wheels include flanges 90 which travel in grooves 86. There is preferably one of these wheels 88 at each corner of the carriage 10 and when the carriage 10 is disposed on the shelves 87 the wheels 88 guide the carriage and prevent lateral movement thereof.

Transversely extending plates 91 are mounted slidably in the slots 84 provided in the rails 82 and mounted on the upper surface of these plates is a longitudinally extending plate 92 which supports a table 93 on which the slab 14 is mounted and this table includes upwardly extending end portions 93'. Suitable connecting elements such as threaded screws 94 secure together for reciprocal movement the slab 14, table 93, plate 92 and plates 91. The heads of these screws are preferably countersunk and the threaded end portions carry threaded nuts 95. A bracket 96 is connected to the plate 92 at the under side thereof by means of suitable screws 97 or the like. A suitable opening is provided in bracket 96 and projecting through this opening and through openings formed in an arm 97 is a pin 98 which carries keys 99 to effectuate movement between the arm 97 and the bracket 96. To effectuate reciprocal rectilinear movement of the abrasive slab 14 and attached units I provide an eccentric arm 100, the upper end portion of which is journaled on a pin 101 which projects through openings provided in arm 97 and in arm 100 and keys 102 are provided in suitable openings formed in the end portions of pin 101. The lower end portion of arm 97 is rotatably mounted on a rod 128 which is mounted in suitable openings formed in the side walls 73 of the housing 12 and this rod provides a bearing surface of the arm 97. Spacing collars 129 are provided on the rod 128.

Provided at the end portion of the eccentric arm 100, opposite the end connected to arm 97, is a suitable split bearing 103 of any approved type and this bearing is mounted on an arm 104 which projects from an eccentric wheel 105. The eccentric wheel 105 is rigidly mounted on and rotatable with a shaft 106 which is journaled in a suitable bearing 107 which is attached to one of the side walls 73 of the housing 12 by means of suitable connecting elements such as screws 108. The shaft 106 projects outwardly from the housing 12 and is connected in any approved manner to a suitable source of motive power such as motor 13. In this connection I provide a housing 109 in which suitable gears are housed for effectuating connection between the motor 13 and shaft 106.

It will be manifest, therefore, that when the glass plates 11 are disposed in position in the carriage 10 and the motor 13 operated the rotatory movement of shaft 106 operated by motor 13 will be converted into reciprocal rectilinear movement by means of the eccentric wheel 105 and arm 100 and thus reciprocal rectilinear movement will be imparted to the polishing slab 14 and attached table 93 which are carried on plate 92. It will be seen, therefore, that when the glass plates 11 are disposed in position in the carriage 10 in the manner described above, with one edge portion of the plates disposed on slab 14, the reciprocal action of slab 14 against the

edges of the plates 11 will effectuate the polishing of the edges of the plates.

In order to prevent any tendency to longitudinal movement of the carriage 10 when the slab 14 and associated parts are in operation I provide bracket arms 110 which are attached to one side wall 73 of the housing 12 by means of suitable connecting elements such as screws 111 and these bracket arms carry a rod 112 on which is mounted a dog 113 and this dog includes a tongue portion 114 which is adapted to be inserted into a notch 123 provided in a block 115 which is secured to the carriage 23 by means of suitable screws 116.

To collect the dust issuing from the plates 11 and the abrasive 14, which may be of any suitable material such as carborundum or the like, I provide receptacles 117 in the housing 12 and communicating with these receptacles are openings 118 provided between chutes 119 and the end walls 74 of housing 12. The chutes 119 are attached to the inner sides of the side walls 73 of the housing 12 in any approved manner such as by welding. It will be seen, therefore, that the dust produced during the grinding and polishing operation will be diverted downwardly between the rails 80 into the receptacles 117 which may be secured to the bottom or end walls of the housing in any suitable manner such as by welding. Further to prevent the escape of dust I provide a housing 120 over the polishing slab 14 and formed in this housing is an opening 121 of suitable size to enable the plates 11 to be lowered therethrough into contact with the polishing slab 14.

Lugs 124 are attached to the housing 12 by means of screws 125 and these lugs include right-angularly extending arms 127 which project inwardly from the side walls 73 of the housing. When the carriage 10 is in position on the housing 12 the arm portions of these lugs rest adjacent the foot portions 30 of the carriage and in this manner prevent the carriage from being tipped sidewardly.

In Fig. 6 a modified form of construction for the polishing slab 14 is provided and in this instance the slab has grooves 122 formed therein in spaced relationship and in use the edges of the plates 14 are disposed in and guided in these grooves.

From the foregoing description of my invention it will be seen that I have provided a glass grinding and polishing machine which is particularly adaptable for grinding and polishing the edges of glass plates such as are used in automotive vehicles or in like uses and which while effectively serving its many other objects will be highly efficient in use and economical in manufacture.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a finishing machine, the combination with a trackway, of a carriage adapted to be moved along said trackway and including means for supporting a plurality of articles to be fin-

ished, finishing mechanism including a trackway onto which said carriage may be moved, said finishing mechanism including a reciprocatory finishing member, and chute members for conveying abrasive material away from said finishing member.

2. In a finishing machine, the combination with a trackway, of a carriage adapted to be moved along said trackway and including means

10 for supporting a plurality of articles to be finished, finishing mechanism including a trackway onto which said carriage may be moved from the first-mentioned trackway, said finishing mechanism including a reciprocatory finishing member, chute members for conveying abrasive material away from said finishing member, and pan members adapted to receive abrasive material discharged from said chute members.

3. In a machine for simultaneously polishing or guiding corresponding parts of the peripheral edges of a plurality of articles, a trackway, a movable abrasive, a carriage for the articles, movable along the trackway, article carrying mechanism mounted on and movable relative 25 to the carriage to and from the abrasive, so that selected corresponding parts of the peripheral edges of the articles may be abraded by the abrasive when the latter is moving, said mechanism holding the articles in the carriage with the selected edge parts thereof in contact with the abrasive, and including means for simultaneously revolving all the articles, when the mechanism is moved from the abrasive, so that other edge parts thereof may be abraded when the mechanism is moved back to the abrasive.

4. An article finishing machine, comprising a movable abrasive, a trackway, an article carriage movable along the trackway to and from

the abrasive, and article-holding means on the carriage movable, relative to the carriage, to and from the abrasive, said means including means for revolving the articles to bring surfaces thereof successively into contact with the abrasive.

5. An article finishing machine, comprising a movable abrasive, a trackway, an article carriage movable along the trackway to and from the abrasive, counterbalanced article-holding means on the carriage movable, relative to the carriage, to and from the abrasive, said means including means for revolving the articles to bring surfaces thereof successively into contact with the abrasive, and a member movably mounted on said carriage for moving said article-holding means relative to the carriage.

6. An article finishing machine, comprising a movable abrasive, an article carriage, article-holding means on the carriage movable, relative to the carriage, to and from the abrasive, means on the carriage counter-balancing the article-holding means, and a member movably mounted on the carriage for moving the article-holding means, relative to the carriage, toward and away from the abrasive.

7. An article finishing machine, comprising a movable abrasive, a trackway, an article carriage movable along the trackway to and from the abrasive, article-holding means on the carriage movable, relative to the carriage, to and from the abrasive, means on the carriage counterbalancing the article-holding means, and a member movably mounted on the carriage for moving the article-holding means, relative to the carriage, toward and away from the abrasive.

HUBERT J. CAPELLMAN, SR.
